UNITED STATES PATENT OFFICE.

WILLIAM H. LANNING, JR., OF TOLEDO, OHIO.

ADJUSTABLE ECCENTRIC.

1,073,148.

Specification of Letters Patent. Patented Sept. 16, 1913.

Application filed March 4, 1912. Serial No. 681,599.

To all whom it may concern:

Be it known that I, WILLIAM H. LANNING, Jr., a citizen of the United States, and a resident of Toledo, in the county of Lucas and State of Ohio, have invented a certain new and useful Adjustable Eccentric; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

My invention relates to eccentrics of the adjustable type, and has for its object the provision of an improved means of this character, which is simple, strong and durable in its construction, and capable of being easily and quickly adjusted to suit the throw desired, thus enhancing its practicability and commercial value.

The invention is fully described in the following specification, and while, in its broader aspect, it is capable of embodiment in numerous forms, a preferred embodiment thereof is illustrated in the accompanying drawings, in which,—

Figure 1 is a cross-section of a shaft with means embodying my invention in elevation thereon and with parts thereof broken away. Fig. 2 is a side elevation of Fig. 1 with parts broken away. Fig. 3 is a view similar to Fig. 1 with the eccentric adjusted for a greater throw, and Fig. 4 is a side elevation of Fig. 3 with a portion broken away.

Referring to the drawings, 1 designates a shaft having, in the present instance, a rectangular portion 2, a substantially centrally located portion of one side of which is recessed or cut away, as at 3, to provide an eccentric or wrist-pin portion 4. The recess 3 preferably extends in depth to the axis of the shaft, as indicated, and the wrist-pin portion 4 is preferably of rectangular form in cross-section, as indicated, and has its outer side projecting slightly beyond the side of the shaft 1 to facilitate the forming of a dove-tailed groove 5 longitudinally therein substantially throughout its length for the purpose hereinafter described. A sleeve 6, having a preferably eccentrically disposed opening 7 longitudinally therethrough of substantially the cross-sectional area and shape of the shaft portion 2, is mounted upon such shaft portion and has

the ends of its opening 7 laterally recessed or enlarged at opposite sides thereof, as shown at 8 and 9. The recesses 8 register with and are of suitable size to permit the crank-arm portions of the shaft part 2 to work therein when the sleeve is placed in the position shown in Figs. 3 and 4, with one side portion thereof seating within the recess 3, in which position the sleeve which forms the eccentric journal of the device has its maximum throw. The sleeve 6 is circumferentially recessed, as at 10, to provide a journal with which the crank end of a plunger may engage, as well understood in the art.

For the purpose of locking the sleeve 6 in the shortened-throw position shown in Figs. 1 and 2, a spring pressed plunger or pin 11 is mounted in an opening 12 in each shoulder 10^a thereof in position for its inner end to work within the associated sleeve recess 8 and engage over the inner ends of the crank arm portions of the shaft part 2, whereby to coöperate with the side wall of the opening 7 with which the outer side of the shaft part 2 coacts to rigidly hold the sleeve 6 in adjusted position thereon, as best shown in Figs. 1 and 2. A stem 13 projects from each plunger 11 without the sleeve through a plug 14 which removably closes the outer end of the opening 12, thus facilitating a withdrawal of each plunger from locking engagement with the shaft part 2 and against the tension of the spring 15.

Key-blocks 16, 16 are carried by the outer side of the shaft portion 2 for sliding movements longitudinally thereof, due to parts thereof working within the complementary dove-tailed groove 5 in the shaft portion, said blocks being adapted to closely fit between the outer side of such shaft portion and the respective side wall of the sleeve opening 7 when the sleeve is in the maximum-throw position shown in Figs. 3 and 4, thus serving to firmly lock the sleeve in such position relative to the wrist-pin 4. When the sleeve 6 is in its shortened-throw position the key-blocks 16 are disposed at the outer ends of the dove-tailed groove 5 and rest neutral within the registering recesses 9, which are disposed at the ends of the sleeve opening 7 in opposition to the recesses therein. The key-blocks 16 are prevented from withdrawal from the ends of the guide groove 5 by the provision of stop-pins 17 or other suitable stop means at the ends of the groove.

The movements of the key-blocks 16 longitudinally of the shaft part 2 are controlled by the rotation of pinions 18, one being provided for each block in an associated end 5 portion of the sleeve 6 and being adapted to mesh with a rack 19 on the adjacent side of the respective blocks when the sleeve 6 is in its maximum-throw position, as indicated in Figs. 3 and 4. The pinions 18 are 10 mounted for rotary and axial reciprocatory movements within sockets 20 provided in suitable position in the shouldered portions 10^a of the sleeve, and the movements of each pinion are controlled by stems 21 which project axially therefrom without the outer ends of the socket 20 through a plug 22, which removably closes the outer ends of the socket, as shown in Figs. 1 and 3. Coiled compression-springs 23 are mounted within 15 the sockets between the pinions 18 and plugs 22 to tend to force the pinions axially into mesh with the respective key-racks 19.

It is evident with this form of adjustable eccentric that to adjust the eccentric for a 25 minimum throw it is only necessary to turn the stems 21 to rotate the pinions 18, which effects an outward movement of the key-blocks 16 into register with the sockets 9 of the sleeve, after which the sleeve may be 30 moved laterally from the position shown in Figs. 3 and 4 to the position shown in Figs. 1 and 2, with the outer side of the shaft part 2 abutting against the registering wall of the sleeve opening 7. Upon a movement 35 of the sleeve 6 into its minimum-throw position the spring-pressed plungers 11 will automatically move into the recesses 8, 8 in the sleeve ends and engage over the respective end portions of the shaft part 2 to 40 rigidly lock the sleeve in such position of adjustment. It is also evident that a vice versa action takes place upon an adjusting of the sleeve 6 from its minimum to its maximum-throw position.

45 I wish it understood that my invention is not limited to any specific construction or arrangement of the parts except in so far as such limitations are specified in the claims.

50 Having thus described my invention, what I claim as new and desire to secure by Letters Patent, is,

1. In combination, a shaft having an ec-

centric portion, a journal member carried by said portion and adjustable transversely 55 thereof in the plane of its projection, key members slidingly carried by said eccentric for movements longitudinally thereof, and means carried by the journal member and operable to move the key members into position to lock the journal member in one position of adjustment relative to the eccentric or to move them into neutral position.

2. In combination, a shaft having an eccentric portion, a sleeve carried by said portion for adjustment transversely thereof to adjust its throw, plungers carried by the sleeve for engagement with the eccentric to secure the sleeve in one position of adjustment, said plungers being operable from 70 without the sleeve to release it from such position of adjustment, and means slidingly associated with the sleeve for coacting with it and the eccentric to secure the sleeve in another position of adjustment relative to 75 the eccentric.

3. In combination, a shaft having a portion which is of polygonal form in cross-section with a side recessed, a sleeve having an eccentric opening therethrough complementary to said shaft portion for fitting thereover and having the end portions of said opening transversely broadened in the plane of throw of the eccentric to permit an intermediate portion of the sleeve to work 85 within the recesses of said shaft portion upon an adjustment of the sleeve to lengthen the eccentric throw thereof, means having parts working within portions of said opening enlargements to coact with parts of the 90 shaft portion to retain the sleeve in one position of its adjustment, and key-blocks carried by said shaft portion for movements longitudinally thereof and operable to move within the sleeve to lock the sleeve in an- 95 other position of adjustment relative to the shaft and being also movable into neutral positions in registering ones of said opening enlargements.

In testimony whereof, I have hereunto 100 signed my name to this specification in the presence of two subscribing witnesses.

WILLIAM H. LANNING, JR.
